LOOM PICKER

James V. Looper, Bessemer City, N. C.

Application March 24, 1952, Serial No. 278,169

9 Claims. (Cl. 139—160)

1

This invention relates to improvements in loom pickers of the type usually associated with multiple shuttle looms and it is the general object of the invention to provide a picker so designed as to reduce the wear on the picker stick and to prolong the useful life of the picker.

Pickers of the type associated with multiple shuttle looms are usually somewhat pear-shaped and molded from leather, plastic or the like or they may even be made from wood. This type of picker is usually mounted on a rod disposed rearwardly of the shuttle box on a loom and on which the picker has longitudinal sliding movement. The picker has a portion thereof which projects through a slot in the shuttle box and serves to engage and throw the shuttle across the lay of the loom. Now, this type of picker is provided with a vertically extending opening having convex side walls and the picker stick extends through this opening and engages either of the walls, depending upon the direction of movement of the picker stick, to thereby impart movement to the picker.

Accordingly, the picker stick engages a relatively small area on the picker as it effects reciprocal movement to the picker and this not only strains the picker stick, at times causing the same to break, but, also, the constant pounding of the picker stick against the convex walls of the opening in the picker through which it extends soon causes the convex walls to become so badly worn as to irreparably damage the picker and to require that the picker be replaced.

In order to overcome such defects, it is another object of this invention to provide a picker of the character last described with a wear plate, preferably made from sheet metal, which is adapted to be pivotally connected intermediate its ends to either of the said convex walls of the opening in the picker through which the picker stick extends, the wear plate projecting beyond the upper and lower surfaces of the picker to thus provide a substantially greater surface to be engaged by the picker stick upon each active stroke of the picker stick and whereby the wear plate will adjust itself to the angularity of the picker stick through the course of its active stroke so the entire length of the wear plate remains in engagement with the picker stick throughout the active stroke of the picker stick thus obviating wearing of the corresponding convex surface of the picker and distributing the force applied by the picker stick over a substantial area to thereby prolong the useful life of the picker stick and the picker.

Some of the objects of the invention having

2

been stated, other objects will appear as the description proceeds when taken in connection with the accompanying drawings, in which—

Figure 1 is a fragmentary top plan view of a portion of a loom showing the shuttle box at one end of the lay of the loom, this shuttle box being of the type usually associated with a multiple shuttle loom, and showing the improved picker in association therewith;

Figure 2 is an enlarged vertical sectional view, taken substantially along the line 2—2 in Figure 1, showing the upper end of the picker stick in phantom or broken lines;

Figure 3 is an isometric view of the improved picker disassociated from the loom;

Figure 4 is another isometric view of the improved picker looking at the opposite side thereof from that shown in Figure 3;

Figure 5 is a fragmentary vertical sectional view, showing the wear plate in elevation, taken substantially along the line 5—5 in Figure 2;

Referring more specifically to the drawings, the numeral 10 generally indicates the frame of a loom relative to which a lay 11 has forward and rearward reciprocatory movement. This lay has a shuttle box 12 to receive and expel a shuttle S carrying a quill or bobbin B from which weft yarn W is withdrawn as the shuttle S is thrown in opposite directions across the lay 11. The shuttle box 12 has front and back walls 13 and 14, respectively, between which the shuttle S is located and the back wall 14 is provided with a longitudinally extending slot therein, defined by the broken lines 15 and 16, through which the improved pear-shaped picker P extends.

The lay also carries a guide rod 17 spaced rearwardly of the shuttle box 12 and the picker P has an enlarged rear or outer portion 19 provided with a longitudinally extending bore 20 therethrough which is slidably penetrated by the rod 17 whereby the picker P has longitudinal sliding movement on the guide rod 17. The picker has an enlarged inner or shuttle bunter portion 21 which is of less length than the enlarged outer portion 19. The portions 19 and 21 are spanned by a relatively thin bridging portion 22 integral therewith and the picker P has an aperture or opening 23 therethrough disposed at the juncture of the enlarged rear or outer portion 19 and the bridging portion 22.

This opening 23 is provided with respective front and rear walls 24 and 25 and opposite substantially convex walls 26 and 27 which walls 24 to 27, inclusive, define the opening 23. It will be observed that the relatively thin bridging portion 22 of the picker P rides in or extends through the

slot defined by the broken lines 15 and 16. The upper end of a picker stick 30 extends through the opening 23 and this picker stick 30 is driven by conventional means, not shown, to move about a pivot point spaced substantially below the shuttle box 12, as is well known, to cause the picker stick 30 to reciprocate between the guide rod 17 and the rear or back wall 14 of the shuttle box 12.

Heretofore, the picker stick 30 has alternately engaged the opposite end walls 26 and 27 of the opening 23 in the picker P and these end walls 26 and 27 have been convex due to the constantly changing angle at which the picker stick 30 engages the walls 26 and 27, since the picker stick 30 is pivoted at its lower end on the loom.

The picker P as heretofore described is conventional as are the associated parts of the loom heretofore described. The improvement in the pear-shaped picker P is embodied in a pivoted wear plate or element 32 which is relatively narrow in proportion to its length so as to have freedom of pivotal movement between the front and rear walls 24 and 25 of the opening 23. In order to accommodate the wear plate or element 32, each of the end walls 26 and 27 of the opening 23 in the pear-shaped picker P is provided with a transverse groove 33 and the central portion of the wear plate or element 32 has a lateral projection 34 formed thereon which also forms a lateral groove or depression 35 in the outer face of the central portion of the wear plate or element 32.

The lateral projection 34 has a curved outer surface which conforms substantially to the curvature of the bottom of the corresponding groove 33 and in which this lateral projection 34 is adapted to have pivotal movement. In order to support the improved wear plate or element 32, a suitable shaft 36 may be provided, which is disposed in the groove 35 in the wear plate 32. This shaft 36 serves to pivotally support the wear plate or element 32 intermediate the upper and lower ends thereof and each of the end walls 26 and 27 has a pair of laterally spaced longitudinally extending holes 40 therein which are penetrated by the legs 42 of the shaft 36. The outer ends of the legs 42 are bent against the outer surface of the pear-shaped picker P to thereby secure the shaft 36 in position in the corresponding pair of holes 40.

It is evident that the shaft 36 may be suitably embedded in the front and rear walls 24 and 25 at opposite ends thereof rather than being made in the form of a staple if desired. However, the staple form shown is believed to embody the most simple and economical manner in which the pivoted wear plate or element 32 may be supported. It will be observed in Figure 4 that opposite sides of the wear plate 32 are cut-away to accommodate the legs 42 of the shaft 36.

Although a single wear plate or element 32 is shown in the drawings, it is evident that a second wear plate of identical configuration may be pivotally supported in the groove 33 in the wall 27 of the opening 23, if desired. On the other hand, if a single wear plate or element is employed as shown in the drawings, upon one end of the bunter portion 21 becoming worn extensively by repeated impacts of the shuttle S, which forms a conical cavity in the bunter portion 21 as shown in Figure 1, the picker P can be turned over so that the opposite end of the shuttle bunter portion 21 may be engaged by the shuttle S as the shuttle is thrown into the shuttle box 12. In the

latter instance, it is evident that the improved pivoted wear plate 32 may be removed from the groove 33 in the wall 26 and supported by the wall 27 in the identical manner in which it is shown as being supported by the wall 26 in Figures 2, 3, 4 and 5.

It is thus seen that there is provided an improved wear plate for loom pickers having means to pivotally support the wear plate intermediate 10 its upper and lower ends on either of the end walls 26 or 27 of the opening 23 in the pear-shaped picker P with the upper and lower ends of the wear plate extending beyond the upper and lower surfaces of the picker P to provide a relatively 15 larger surface area for engagement by the picker stick 30 in the course of each active stroke thereof and the pivotal connection serving to permit the wear plate to automatically adjust itself to the varying angularity of the corresponding 20 surface of the picker stick in the course of each active stroke of the picker stick. It is evident that this will greatly prolong the useful life of both the picker stick and the picker as compared to the use of picker sticks with pickers of the type 25 heretofore in use.

It might be stated that the upper and lower edges of the end walls 26 and 27 are cut-away to provide the convex surfaces with less radii than that of the end walls on the usual pear-shaped pickers in order to provide ample clearance 30 to permit sufficient pivotal movement of the wear plate 32 whereby the wear plate can adjust itself to the extreme angular positions occupied 35 by the picker stick 30 in the course of its reciprocating movement. It is to be noted that the upper and lower edges of the wear plate are also beveled or rounded to prevent damage to the picker stick 30.

In the drawings and specification, there has 40 been set forth a preferred embodiment of the invention and although specific terms are employed, they are used in a generic and descriptive sense only and not for purposes of limitation, the scope of the invention being defined in the claims.

45 I claim:

1. In a picker for looms, said picker having a vertically extending opening defined by side walls and end walls through which a picker stick is adapted to extend, the combination of a wear plate, means pivotally securing the wear plate intermediate its upper and lower ends to one of the walls of the opening of said picker, and the upper and lower ends of the wear plate extending 50 at least as far as the upper and lower surfaces of the picker to protect the picker stick in the course of each active stroke of the picker stick in engagement therewith.

60 2. In a picker for looms, said picker having a vertically extending opening therethrough

65 through which a picker stick is adapted to extend, said opening being defined by side walls and opposite end walls, the combination of a wear plate adapted to be disposed between the side walls of said opening, at least one of the side walls having a transverse groove intermediate its upper and lower ends, said wear plate being formed from relatively thin strap material and having a depression formed in one side thereof, said depression also forming a projection on the opposite side of said wear plate, a means 70 carried by the picker and disposed in said groove 75 for pivotally supporting the wear plate inter-

mediate its ends, said projection on the wear plate being adapted to be disposed in the groove in the corresponding end wall of the opening and the opposite ends of the wear plate extending beyond the opposite surfaces of the picker whereby the wear plate will serve to protect the picker stick and will adjust itself to the angularity of the picker stick during movement of the picker stick.

3. In a picker for looms, said picker having a vertically extending opening therethrough for loosely receiving the upper end of a picker stick, the combination of a wear plate adapted to have its medial portion extend through said opening against a corresponding wall of said opening, said wall having a horizontal groove therein, a lateral projection on one side of said wear plate adapted to slidably fit in said groove, said wear plate having a lateral groove in the other side thereof adjacent said projection, a shaft adapted to fit in the groove in the wear plate for pivotally supporting the wear plate and said shaft having leg portions embedded in said wall of the opening.

4. In a picker for looms, said picker having a vertically extending opening therethrough defined by spaced side walls and spaced end walls, a picker stick adapted to loosely penetrate said opening and said end walls being convex; the combination of a wear plate supported against at least one of said end walls, the latter end wall having a transverse groove therein of substantially semi-circular cross-sectional configuration, a transverse projection on said wear plate and also being of substantially semi-circular cross-sectional configuration to fit for pivotal movement in said groove, and means to pivotally retain said transverse projection in said groove.

5. In a picker for looms, said picker having a vertically extending opening therethrough defined by spaced side walls and spaced end walls, a picker stick adapted to loosely penetrate said opening and said end walls being convex; the combination of a wear plate supported against at least one of said end walls, the latter end wall having a transverse groove therein of substantially semi-circular cross-sectional configuration, a transverse projection intermediate the opposite ends of said wear plate and also being of substantially semi-circular cross-sectional configuration to fit for pivotal movement in said groove, and means to pivotally retain said transverse projection in said groove.

6. In a picker for looms, said picker having a vertically extending opening therethrough defined by spaced side walls and spaced end walls, a picker stick adapted to loosely penetrate said opening and said end walls being convex; the combination of a wear plate supported against at least one of said end walls, the latter end wall having a transverse groove therein of substantially semi-circular cross-sectional configuration, a transverse projection intermediate the opposite ends of said wear plate and also being of substantially semi-circular cross-sectional configuration to fit for pivotal movement in said groove, means to pivotally retain said transverse projection in said groove, and the opposite ends of said wear plate extending beyond the opposite surfaces of said picker.

7. In a picker for looms, said picker having a vertically extending opening therethrough defined by spaced side walls and spaced end walls, a picker stick adapted to loosely penetrate said opening and said end walls being convex; the

combination of a wear plate supported against at least one of said end walls, the latter end wall having a transverse groove therein of substantially semi-circular cross-sectional configuration, a transverse projection on said wear plate and also being of substantially semi-circular cross-sectional configuration to fit for pivotal movement in said groove, said wear plate having a transverse groove in the surface thereof opposite to the surface having the projection thereon and being in the same plane as said projection, and a shaft carried by said picker and extending through said last-named groove to pivotally support said wear plate with the projection thereon disposed in the first-named groove.

8. In a picker for looms, said picker having a vertically extending opening therethrough defined by spaced side walls and spaced end walls, a picker stick adapted to loosely penetrate said opening and said end walls being convex; the combination of a wear plate supported against at least one of said end walls, the latter end wall having a transverse groove therein of substantially semi-circular cross-sectional configuration, a transverse projection intermediate the opposite ends of said wear plate and also being of substantially semi-circular cross-sectional configuration to fit for pivotal movement in said groove, said wear plate having a transverse groove in the surface thereof opposite to the surface having the projection thereon and being in the same plane as said projection, and a shaft carried by said picker and extending through said last-named groove to pivotally support said wear plate with the projection thereon disposed in the first-named groove.

9. In a picker for looms, said picker having a vertically extending opening therethrough defined by spaced side walls and spaced end walls, a picker stick adapted to loosely penetrate said opening and said end walls being convex; the combination of a wear plate supported against at least one of said end walls, the latter end wall having a transverse groove therein of substantially semi-circular cross-sectional configuration, a transverse projection intermediate the opposite ends of said wear plate and also being of substantially semi-circular cross-sectional configuration to fit for pivotal movement in said groove, said wear plate having a transverse groove in the surface thereof opposite to the surface having the projection thereon and being in the same plane as said projection, and a shaft carried by said picker and extending through said last-named groove to pivotally support said wear plate with the projection thereon disposed in the first-named groove, and the opposite ends of said wear plate extending beyond the opposite surfaces of said picker.
